UNITED STATES PATENT OFFICE.

DENNIS PARKS, OF ST. LOUIS, MISSOURI, ASSIGNOR TO MITCHELL-PARKS MANUFACTURING COMPANY, OF ST. LOUIS, MISSOURI, A CORPORATION OF MISSOURI.

MOLDING-MACHINE.

No. 911,066.

Specification of Letters Patent.

Patented Feb. 2, 1909.

Application filed February 10, 1908. Serial No. 415,138.

To all whom it may concern:

Be it known that I, DENNIS PARKS, a citizen of the United States, residing at St. Louis, in the State of Missouri, have invented new and useful Improvements in Molding-Machines, of which the following is a specification.

This invention relates to an improvement in molding machines of the type in which the sand is packed in the flask about the pattern by means of jarring, and has for its object to provide a machine of this type in which the weight of the flask containing the sand, and of the parts supporting the flask, shall be substantially counterbalanced, so that the flask with its support may be raised or lowered to accomplish the jarring effect with the expenditure of but little power and the production of a minimum of shock or vibration.

The machine as described and illustrated is adapted more especially for making small castings, and it is intended it shall be operated manually. The invention, however, is not limited to this special character of machine, nor to such mode of operation. In other words, the invention herein defined would, as to the principles involved, as defined in the claims, apply equally well to a machine for making large castings and operated by mechanical power. So far as I am aware, machines of this general type have been of great weight, and have required the employment of considerable power to operate them, and usually a specially constructed foundation or base of great firmness to withstand the shocks produced in operation.

Furthermore, the full weight of the movable part of the machine with the flasks and sand was exerted on the fixed part of the machine in jarring the sand, resulting in the production of such extreme shocks or vibrations, that very frequently the sand in the flasks, which had been packed, and which would be resting on the foundry floor, would be shaken loose, necessitating repacking of such flasks.

It will be obvious that the weight of the flasks, or the part supporting the flask, has no effect whatever in packing the sand, and that it is the weight of the sand itself which causes the packing thereof when the jar is produced. Therefore, it is apparent that the weight of the flask and its movable support may be counteracted, thus obviating to a large extent shocks and vibrations, without in any manner affecting the packing of

the sand, and further, that the weight of the sand itself in the flask may be to a greater or less extent counteracted or even substantially counterbalanced, leaving the degree of shock or the force of the impact to be imparted to the flask to be determined by the power expended by the operator, whether this power be exerted manually or otherwise.

In the drawing:—Figure 1 is a view in end elevation of a molding machine constructed according to my invention. Fig. 2 is a view in front elevation of same. Fig. 3 is a section on the line 3—3 of Fig. 2.

The device is constructed in large part of cast iron, and comprises side frame members 1, which are connected at their upper ends by two flat bars or plates 2, one on either side of the machine. On the outer side of each of the side frames, guide-bearings 4 are provided in which works a rod 5. The upper end of each of these rods has extending through it the screw-thread end of a bolt 5^a, on which is mounted a binding-wheel 6. Pivotally supported on each of the bolts 5^a is a cast iron head 7, said heads being connected by means of bars or plates 8, secured to the bottom of the heads on either side thereof, and having the same width as the bars 2. The bars 8 support the board 9 containing the pattern, and may be held in position by any preferred means.

10 indicates the flask, which is placed on the pattern board 9, and which is held in position by means of a bar 11 engaging under cleats 12, one of which is adjustably secured on the upper side of each of the heads 7 as shown. The binding wheels 6 are for the purpose of securing the heads 7 in a fixed position, and, on being loosened, to permit said heads to be rotated on their pivots to reverse the position of the flask. As shown in Fig. 2 the machine may be adapted to accommodate two flasks, one of which may be the cope and the other the drag.

Pivotally connected to each of the rods 5, intermediate the ends of the latter, as indicated at 13, is a lever 14, the lower end of which is pivotally connected to a short crank-arm 15, which latter is in turn mounted in the side frame member by means of a bolt 16. The construction is the same on each side of the machine, and the crank arms 15 are rigidly connected by a cross beam 17. On this cross beam is secured a treadle 18. 19 indicates a coil spring which is adjustably secured at its

upper end by means of a threaded bolt 20 centrally of a frame-member 21 and at its lower end is secured in the cross-beam 17. The tendency of this spring is to lift the rods 5 and with them the heads supporting the flask; and the strength of this spring is such that when the flask has no sand in it the flask support will be held above the bumper plates 2, and the spring will be practically 10 fully retracted. When the flask is filled with sand, however, the weight thus added will be sufficient to depress the rods 5 against the resistance of said spring, the adjustment of the tension of which is such that the bars 8 supporting the flask will rest lightly on the bumper plates 2. In other words, the weight of the sand will be just sufficient to overcome the tension of the spring, and the flask support, and the flask or flasks of sand thereon, 15 will have their weight substantially counterbalanced. After the sand is placed in the flask, or flasks, the operator by placing his foot on the treadle 18 may easily lift the flask support through the medium of rods 5 and 20 the lever mechanism described, and then by releasing pressure on the treadle permit the flask support to drop, the jar resulting from the impact of the bars 8 with the bumper plates 2 causing the sand in the flask to pack 25 about the pattern to a greater or less degree. This operation is repeated as often as may be necessary to pack the sand to the extent desired. The subsequent manipulation of the flask by raising the flask support and reversing the same is well known and need not be 30 described.

I claim:

1. A machine for molding sand by jarring embodying a substantially counterbalanced 40 reversible member movable into and out of contact with a fixed part of the machine.
2. A molding machine for packing sand in a flask by jarring comprising, in combination with the frame of the machine, a spring-supported movable and reversible flask support. 45
3. In a molding machine, in combination with a reciprocable and reversible flask support, means for substantially counterbalancing the weight of said support with the 50 flask of sand thereon.
4. In a molding machine for packing sand in the flask by jarring, a reciprocable and reversible flask support, a resilient member normally supporting the weight of said support and adapted to substantially counterbalance 55 said support when the flask of sand is mounted thereon.
5. In a molding machine for packing sand

by jarring, in combination with a reciprocable and reversible flask support, a spring normally supporting the weight of said support, and having a tension sufficient to substantially counterbalance said support when the flask of sand is mounted thereon. 60

6. In a molding machine, in combination 65 with a reciprocable and reversible flask support adapted, by impact with a fixed part of the machine to pack by jarring sand in the flask mounted thereon, a spring normally holding said support out of contact with said fixed part and adapted to yield under the weight of the sand placed in the flask to permit the support to come in contact with said fixed part, and means for reciprocating said support. 70

7. In a molding machine, in combination 75 with a fixed part of the machine, reciprocable members mounted in the frame of the machine, a flask support mounted on said members and reversible thereon, a spring interposed between the fixed part of the machine and said members tending normally to raise the latter, and means for reciprocating said members to cause said flask support to be brought into and out of contact with the 80 fixed part of the machine for the purposes described.

8. In a molding machine, in combination 85 with a fixed part of the machine, a reciprocable flask support, mechanism for manipulating said flask support so that it may by gravity contact with said fixed part and by impact pack the sand in the flask mounted on said support, and means connected to the fixed part of the machine and the flask manipulating mechanism counter-balancing the 90 flask and the flask support for the purposes described.

9. In a molding machine, in combination 95 with a fixed part of the machine, reciprocable members mounted in the frame of the machine, a flask support mounted on said members, mechanism for reciprocating said members whereby the flask support may be brought into and out of contact with said 100 fixed part of the machine, and means tending normally to raise said reciprocable members and to substantially counter-balance said support with a packed flask thereon.

In testimony whereof I have hereunto set 110 my hand in presence of two subscribing witnesses.

DENNIS PARKS.
